Primary Examiner—Nelson C. Holtie*Assistant Examiner*—Martha Thompson*Attorney, Agent, or Firm*—James A. Drobile; Robert A. Koons; Robert E. Rosenthal**[57] CLAIM**

The ornamental design for a combined file box organizer for assorted desk articles, as shown and described.

DESCRIPTION

FIG. 1 is a top, left front perspective view of a combined file box and organizer for assorted desk articles showing our new design;

FIG. 2 is a front elevational view;

FIG. 3 is a rear elevational view;

FIG. 4 is a top plan view;

FIG. 5 is a bottom plan view;

FIG. 6 is a right side elevational view, the left side being a mirror image thereof;

FIG. 7 is a top, left front perspective view with the lid member in an opened position;

FIG. 8 is a top plan view of FIG. 7; and,

FIG. 9 is a top plan view with the cover member removed for convenience of illustration.

FIGS. 2 through 6 and 8 and 9 have been drawn to an enlarged scale with respect to FIGS. 1 and 7.
